(57) **CLAIM**

The ornamental design for a wall storage rack, as shown and described.

DESCRIPTION

FIG. 1 is a top, left perspective view of a wall storage rack showing my new design;

FIG. 2 is a left side view thereof;

FIG. 3 is a right side view thereof;

FIG. 4 is a bottom view thereof;

FIG. 5 is a front view thereof;

FIG. 6 is a top view thereof;

FIG. 7 is an exploded perspective view thereof; and,

FIG. 8 is a perspective view thereof shown in use.

Any shading is not features of the design but are utilized to illustrate the surface contours of the wall storage rack design in the drawings. The broken lines shown in the figures are for environmental purpose only and form no part of the claimed design.

1 Claim, 8 Drawing Sheets
